UNITED STATES PATENT OFFICE.

POWEL CROSLEY, JR., OF CINCINNATI, OHIO.

RHEOSTAT.

Application filed October 9, 1922. Serial No. 593,403.

My invention relates to rheostats, and more particularly to those for use in circuits of low voltage, as in radio receiving sets or any other installation where a large number of relatively small variations of resistance are required, to afford appreciable variations of current with such low voltage.

The object of my invention is to provide a simple, compact, and inexpensive rheostat, easy to install, especially under the conditions encountered in supplying parts of apparatus to various users who assemble them variously to suit their own wishes. A further object, preferably, is to insure durability of the rheostat both as to the effects of mechanical wear and electrical effects, including heating. Other objects will appear in the course of the ensuing description.

I attain these objects by the device illustrated, for example, in the accompanying drawing, in which—

Figure 1 is a rear or inside elevation of a rheostat embodying my invention, parts of the cabinet or support and of the lead wires or buss-bars being shown in their relation thereto, and the rheostat being adjusted to include about one-half of its resistance in the circuit;

Fig. 2 is an upright section on the planes of the broken line 2—2 of Fig. 1;

Fig. 3 is a view similar to Fig. 1, showing a modification;

Fig. 4 is an upright section on the planes of the broken line 4—4 of Fig. 3;

Fig. 5 is a detail perspective view of the mounting of Figs. 3 and 4;

Fig. 6 is a fragmentary view showing the connection of the core to the mounting and the way in which the resistance wire is led out at this connection;

Fig. 7 is a partial section similar to Figs. 2 and 4, showing a second modification; and

Fig. 8 is a similar view showing a third modification.

In all of the examples, the core 1 is curved into almost a complete circle with its ends almost meeting, thus being annular in form. Its cross-section, as shown, is that of a flat rectangle with its lesser dimension radial to the curving, so that it presents one of its broad flat sides radially inwardly, as the concave side of the curved body. Such a core has an insulating surface; and preferably it is entirely of insulating material.

The most desirable material for this core is insulating material that may readily be

bent to the curved or annular form, such as hard rubber, fiber, or any of the numerous insulating compositions of this character.

The resistance wire 2 preferably is of a metal or alloy having a high specific resistance to electrical current, a low temperature coefficient, and resistance to wear and corrosion. Such wire being readily obtainable on the market, further description thereof herein will be unnecessary. This wire, or any suitable wire, of the gauge appropriate to afford the desired resistance, has one end part 3 passed through the insulating core 1 a material distance from one end of the core, and clinched or otherwise suitably secured, without electrical connection to any other conductor. This wire 2 is wound uniformly, in spaced turns, usually a little farther apart than the diameter of the wire, around the core 1, preferably before the core is bent to its curved or annular form; and the opposite end part 4 of the wire 2 is passed through the core 1, from the outer to the inner side, near the opposite end of the core, for electrical connection as will be described. The wire being tightly wound on the core, its turns will partake substantially of the rectangular outline of the core cross-section, and will be stretched firmly across the inner or concave side of the core at substantially equal intervals, so that by making electrical connection with any one of these turns along this inner side, this turn and all turns between this and the electrically connected end 4 can be included in the circuit.

As shown in the first example, Figs. 1 and 2, the mounting 5 is a shallow cup having an insulating surface, and preferably made entirely of insulating material of a rigid nature; as, for example, porcelain or other earthenware, or glass. The core 1, with its wire 2 wound thereon, fits snugly in this cup mounting 5, and fastening elements or screws 6 and 7 pass through the wall of the cup and through the end parts of the core 1. Preferably, these screws pass through from the inside, so that their heads are inward; and outside they receive nuts 8 by which the core ends are firmly clamped to the cup wall. By allowing these screws to project beyond their nuts 8, their ends may readily contact with the electrical connectors or buss-bars 9 by which the rheostat is included in the desired circuit.

The screw 6 passes through the core end

part next to the resistance wire end 4, and receives a loop of this end under its head; thus forming one terminal of the rheostat.

Substantially concentric with the annular core and resistance wire coiled therearound, and, in Figs. 1 and 2, with the annular wall of the cup shaped mounting 5, the shaft 10 passes through the mounting; which mounting 5 is fastened to the panel 11, understood to form, along with the base 12, a part of the cabinet or other support in which the rheostat, along with other instruments, is installed. This shaft 10 has on its outer end the knob 13, tightly secured thereto so that the shaft 10 will turn with the knob in either direction; and also, preferably, the knob and shaft carry with them a pointer 14 which serves to indicate, at the outside, the setting of the rheostat, which, in practice, is concealed inside the cabinet or behind the panel. As here shown, a small bolt or screw 15 secures the mounting 5 to the panel 11, with its head outside, just below the knob 13; and this head serves as a stop for the pointer 14, thereby stopping the knob and shaft.

In the example of Figs. 1 and 2, the carrier or guide 16 is cylindrical, with a bore from end to end, axially thereof; its exterior diameter being reduced about midway of its length, forming a shoulder 17. It has a transverse bore through its larger part, receiving the inner end part of the shaft 10 snugly; and a small set screw 18 is tapped into the adjacent end of the axial bore, to engage in a depression 19 properly located in the shaft 10 to maintain the correct relative positions of the guide 16 and the pointer or index 14. Between this guide 16 and the inner face of the mounting 5, a connector spring 20 has one end part 21 coiled around the shaft 10, with a washer 22 between its free end and the guide 16; the main part of this connector-spring 20 lying against the face of the mounting 5 and extending substantially straight thereacross, out to the cup wall adjacent to the other fastening element or screw 7, where it is bent up along the wall, with a loop around and clamped under the head of this screw 7. Thus the other terminal of the rheostat is formed.

The axial bore of the guide 16, from the transverse shaft-receiving bore out to the smaller end of the guide, is smooth; and the plunger or contact element 23 comprises a stem sliding in this smooth bore, and a convex head 24 lying out against the aforescribed inner parts of the turns of the resistance wire 2. A spring 25 is coiled around the reduced part of the guide, compressed between the under side of the head 24, which preferably is flat, and the shoulder 17. This spring presses the contact element 23 radially outward for firm contact of its head with each successive turn of resistance wire

2, even though the curve of the core 1 and this conforming coiled wire 2 be not uniform, so that its radius, taken from the center of the shaft 10, varies materially. The coiled spring 25 carries the current as part 70 of the connection including the larger part of the guide 16, the washer 22, and the connector-spring 20; and it will be seen that this spring 25, as well as the spring 20, may be amply heavy to avoid fusing or 75 annealing from the heating effect of the current. Also, they are of good conducting metal, as brass or bronze, preferably, further avoiding rise of temperature in these springs. The spring 20, by virtue 80 of its part 21, permits the rheostat to be installed on panels or other supports of various thicknesses yet holds the parts firmly, with the knob 13 back against the face of the panel or support. Thus, if the panel 11 in Fig. 2 were thicker, the spring part 21 would be more compressed. To permit installation on a much thicker panel or support, the shaft 10 may have an additional depression 19' nearer its end, in line with the first depression 19; thus receiving the set screw 18 and avoiding excessive compression of the spring part 21. However, in practice, most panels are thin enough to avoid the need of such extra depression 19'. 85 Since the contact element 23 may properly contact with the inner parts of the resistance wire 2 anywhere across the inner or concave face of the core, the variations due to mounting on various thicknesses of panels do not 90 affect the nature of the contact; and any slight axial motion of the shaft 10, permitted by such a spring control, merely allows the contact element 23 to travel in different zones, avoiding concentration of the 95 wear on the wire 2 and thus adding to the durability of the rheostat. The cup mounting 5 maintains the core 1 and its wire 2 in close approximation to a truly circular 100 shape, avoiding much of the radial variation 110 which the spring 25 compensates for; thus permitting a more even pressure of this spring and accordingly a more uniform contact with the wire 2. Also, it may act as a protector of the core and wire, as well as 115 a protector of adjacent objects from the heat generated in the resistance wire 2; as for instance should the panel 11 be of wood, or other combustible material. Such protection is more desirable, if the voltage is such 120 as to heat the wire excessively; in which case, also, the core should be of insulating material able to withstand this heat.

However, in the use of this rheostat in radio receiving sets, and similar installations, the heating of the wire 2 is not such as to require these precautions; and the outside protection against heat is not needed. For the core, a fiber or the like, not softened by the heat, is preferable to hard rubber or 130

the like. But even with wood panels 11, the heat from the wire 2, in these installations, is not dangerous. Therefore, in most cases, I prefer to dispense with the cup-shaped mounting 5; and although this allows the core 1 and wire 2 to assume a less circular form in the ordinary process of manufacture of these rheostats, the improved contact mounting is found readily to compensate for even a very large amount of this distortion from a truly circular form, and to afford a practically uniform contact under these conditions.

Thus, in Figs. 3 to 6, inclusive, the core 1 carries the wire 2 with its ends 3 and 4 secured as in the first example; but the mounting 5' is a flat, relatively wide strip of metal bent with one part 26 at right angles to the other larger part 27 (Fig. 5,) which smaller part 26 has a small opening 28 and a larger opening 29. The smaller opening 28 receives the fastening means or screw 7 for the core end part where the resistance wire 2 is not connected; and the larger opening 29 receives an insulating bushing 30 around the screw or fastening means 6 extending therethrough and fastening the other core end part to the mounting 5', with the other end of the wire 2 having a loop clamped under the head of this screw 6. The core 1 is thus fastened to the smaller part 26 the mounting 5' with the larger part 27 extending radially inward and having an opening 31 near its end receiving the shaft 10, and a smaller opening 32 about midway from this opening to the smaller part 26, receiving the bolt or screw 15' that secures the mounting 5' to the support or panel 11, with its head outside and just below the knob 13 and pointer 14, acting as a stop therefor, as in the first example. Since the mounting 5' is a conductor, from the shaft 10 out to the terminal screw 6, the connector-spring of the previous example is here replaced by a mere coiled spring 21' around the shaft 10, against the face of the conducting mounting 5', with the washer 22 between it and the contact-element guide mounted on the shaft 10. The fastening screws 6 and 7 carry the clamping nuts 8, and in addition, the lock nuts 33, clamping the lead wires 9'. However, it will be seen that the kind of terminal connection shown in Figs. 1 and 2 may be used here, or this connection may be used in Figs. 1 and 2; or any suitable connection may be used in either example.

Also, it will be understood that the guide and contact element and spring arrangement, for contacting with the inner parts of the wire 2, as shown in Figs. 1 and 2, may be used whether the cup mounting 5 of that example, or the conducting mounting 5' of the present example, be used. However, I have taken occasion, in this second example,

to show a modification of this contact arrangement. The guide element 16' is cylindrical, but of uniform exterior diameter from end to end; while its axial bore is large, and extends from its free end only partly 70 inward to the transverse shaft-receiving bore. Its opposite end is conical and has a hole inclined to the shaft 10, tapped to receive a set screw 18 inclining out over the rim of the core and wire structure, affording 75 better access to the screw head. The shaft 10 has the depressions 19 and 19'; and it will be understood that the second depression 19' may be omitted where the thickness 80 of panels or supports 11 does not vary much, as previously noted. The screw 18, engaged in either depression 19 or 19', holds the guide 16' to turn with the shaft 10, in proper position relatively to the pointer 14, as in the previous example. The contact element 23' comprises the convex head 24', but its stem is larger, to slide in the larger axial bore of the guide 16'; and the spring 25' is inside this bore between the inner end 85 of the stem and the end of the bore, instead of outside the guide as in Figs. 1 and 2. This spring should be amply large to carry the current; and the larger bearing of the enlarged contact element stem in the guide also may be depended upon to afford conductivity directly from contact element 23' to washer 22, spring 21' and conducting mounting 5', relieving the spring 25' of 90 some of the current. It also will be understood that this contact, guide and spring 100 combination may be used where the cup-shaped mounting of Figs. 1 and 2 is used.

In Fig. 7, the guide element 16'' is similar to that of Figs. 3 and 4, but its axial bore is still larger; and the contact element 23'' is a deep cylindrical cup or shell with its bottom 24'' convex outside to bear against the wire 2 as the shell slides in the guide bore and encloses the spring 25'' compressed between the inside of the shell bottom 24'' and the inner end of the guide bore. This affords an even larger contact between the contact element and its guide, than in Figs. 3 and 4.

In Fig. 8, the shaft 10' is slotted diametrically, from its inner end an ample distance, and also threaded near its inner end. The guide element 16'' comprises a tubular radially outer part, and a flat part 34 fitting snugly in the shaft slot and held therein against the pressure of the spring 21' on the washer 22, by a nut 35 screwed on the shaft and having a diametrical notch 36 in which the edge of the flat part 34 engages, locking the nut 35 under the pressure of the spring 21'. Such a guide element 16'' is readily made by flattening part of a tube, allowing the unflattened part to form the tubular part of the guide. Thus, a shoulder 37 will be formed at each side where the unflattened 125

part is the larger, to bear in against the shaft 10'; and where the flattened part is wider than the unflattened part, shoulders 38 are formed at opposite sides, facing radially outward. These serve for the abutment of the inner end of the spring 25^a which surrounds the tubular part with its outer end against the under side of the head 24^a of the contact element 23^a having its 10 stem sliding inside the tubular part of the guide 16^a; in this respect being similar to Figs. 1 and 2, with a relatively small bearing between the contact element and its guide; but permitting the 15 spring 25^a, thus outside the guide, to be amply heavy to carry the current without overheating. Since the parts are held by the nut 35, which may be screwed along the shaft and locked at any half-turn, this construction, including the spring 21', permits 20 a nicer adjustment to panels or supports 11 of different thicknesses, than in the previous examples. Also the parts are considerably lighter than are permitted by the previous 25 examples, especially as compared with those of Figs. 3 and 4, and Fig. 7.

It will be understood that either contact and guide and spring construction, of Fig. 7 or Fig. 8, may be used with the cup mounting of Figs. 1 and 2, although they are here illustrated as used with the bracket shaped mounting of Figs. 3 to 6, inclusive, only parts of which are shown in these views. Also, under different conditions, other modifications than any of the numerous examples herein given may occur, and variation in materials may be desirable or necessary, as well as in the shape or number of parts. Therefore, while certain constructional 40 tails are deemed preferable in connection

with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

In a rheostat, a curved supporting core, 50 resistance wire around said core, a mounting to be attached to any one of a number of supports of various thicknesses, electrically conducting fastening means by which both ends of said core are attached to said mounting, said resistance wire having one end electrically connected to one of said fastening elements, a shaft turning in said mounting approximately coaxial with the curve 55 of said core and extending through the support to which the mounting is attached, a knob on said shaft on the side of said support remote from said mounting, a guide mounted on said shaft to turn therewith, a spring compressed between said guide and said mounting to hold said knob against the support although the thickness of the support varies, said guide and said spring being electrically conductive and said spring being 60 electrically connected with the other fastening element and with said guide, a contact element guided by said guide to move radially outward, and a spring in electrical connection with said contact element and with 65 said guide, pressing said contact element out 70 in direct contact with successive turns of said wire along the inner or concave side of said core, as said shaft is turned.

POWEL CROSLEY, JR.
